UNITED STATES PATENT OFFICE

HAROLD S. ASHENHURST, OF CHICAGO, ILLINOIS, ASSIGNOR, BY MESNE ASSIGNMENTS,
TO INSULEX CORPORATION, OF CHICAGO, ILLINOIS, A CORPORATION OF DELAWARE

METHOD OF MAKING INSULATING BLOCKS IN THE FIELD

Original application filed September 10, 1924, Serial No. 736,893. Divided and this application filed
March 3, 1925. Serial No. 12,882.

This application is a division of my co-pending application, Serial No. 736,893, filed September 10, 1924.

It is the object of my present invention 5 to provide an improved method of making insulating blocks ready to be applied to a wall structure near at hand, thereby avoiding the expense and trouble of shipping the blocks, avoiding the danger of breakage in 10 transit, avoiding the necessity of providing space and time for the drying of the blocks after they are formed and before they are used, and affording the possibility of providing a better fit and more ready application of the block tightly in position where it is to serve. It is another object of my invention to provide that the resulting blocks and wall may be of high insulating and fire-proofing value.

20 The invention will be more readily understood by reference to the accompanying drawings, in which;

Fig. 1 is a perspective view of a temporary form with a quantity of the block-forming material therein;

Fig. 2 is a transverse sectional view through a vertical wall to which the insulating blocks have been applied against an outer sheet or wall;

30 Fig. 3 is a similar view showing a construction in which the blocks are applied against lath secured to the studding on the inside, and,

Fig. 4 is a view showing a method of construction in which plaster is directly applied to the blocks to provide a wall surface.

According to the method here disclosed, I provide at a point adjacent to the wall to be insulated, a plane horizontal surface, such as 40 a floor 9, and place thereon side members 10, 11, 12 and 13, thereby defining a shallow, rectangular, open-top space, the depth of the side members being preferably equal to the thickness of the blocks to be formed. I then place in the bottom of the space a facing member for the block in the form of a strip of building paper 14, and pour thereon a plastic mass composed of gypsum as the major ingredient, and chemicals that in the 45 presence of water will evolve a gas and cause

the expansion of the mass under such conditions that the mass is adapted to set and harden in expanded cellular condition, as described and claimed in my prior reissue Patent No. 15,952, of November 25, 1924. I wish 55 it distinctly understood, however, that I contemplate the employment of any material by means of which a quick-setting cellular block of light weight may be formed.

When the material has risen and before 60 setting is complete, I prefer to level off the top surface, either by screeding or trowelling. By this means I not only provide a level top surface but also strengthen the surface by breaking down the cellular formation.

Shortly after the initial setting takes place, which occurs within 15 or 20 minutes after pouring, and while the material is still relatively soft and wet, I subdivide the large block along the lines 15, into a 70 plurality of smaller blocks 15a, of the desired size and shape. This is easily accomplished by employing a straight-edge and a thin blade that will pass through the cellular material and the paper at the bottom 75 thereof. Thereafter I remove one or more of the side members, preferably the member 13, and lift the adjacent block from its position. The paper 14, adheres strongly to the block and serves as a reinforcement or base 80 for the block. It will be understood that at this time the block is relatively soft, and without sufficient rigidity to resist any substantial shocks or strains.

Immediately thereafter, if desired, the 85 blocks may be placed in a wall and in the drawings I have illustrated a plurality of studs 16, the space between which will preferably correspond to the width of the blocks. The blocks are removed from the adjacent 90 mold and placed in superposed relation to complete the wall to the desired height. Preferably the blocks are placed in position against a wall or sheathing with the adhering paper outside. Thereafter a quantity of cement or plaster is forcibly thrown into the 95 corners and will strongly adhere to the studding and the paper. This cement is indicated at 17.

In Fig. 2 I have illustrated a wall having 100

an outer sheathing 18, suitably secured to the studding and the insulating blocks are placed against this wall with the paper backing on the exposed side. Of course, if desired, blocks may be formed of such thickness as to completely fill the space between the studding, but for ordinary purposes this will be found unnecessary. If it be desired to provide a wall to which plaster may be applied, the blocks, indicated at 15b in Fig. 4, are so placed that a surface other than the surface covered by the paper is placed flush with the surface of the studding. If strips of metal lath 19a are tacked to the studding, plaster 20 may readily be applied to the entire surface.

In Fig. 3 a construction is shown in which the outer sheathing or covering has not been applied. However, metal lath, indicated at 19, has been applied to the inner surface of the studding and the blocks 15a are placed thereagainst. It will be understood that the open side of the wall will be completed in any desired manner.

While I have shown a wall having studs between which the blocks are received, it will be understood that I contemplate the insulation of a wall in the described manner regardless of the structural characteristics of the wall. It is practical in some instances to build the wall without studding, merely placing the blocks in proper relation, one upon another. It is also possible to construct a wall having relatively narrow studding and to completely imbed the studding in the blocks by shaping the blocks around the studding in the process of building. Such construction is not, however, claimed in the present application. It will be understood that while I have illustrated a method by which the blocks are formed by subdividing a larger block that is cast in the field, a desirable result might be secured by separately casting the several blocks in the field in the described manner.

I have had very good results in the practice of my improved method by the use of a mixture of the following ingredients.—100 pounds of calcined gypsum, 2 ounces of commercial retarder, 3½ pounds of a suitable carbonate such as calcium carbonate, and 8 pounds of aluminum sulphate containing its water of crystallization, all of such ingredients being finely ground and thoroughly mixed in a dry state.

I do not wish to claim by this application the subject-matter disclosed and claimed by my copending applications, Serial No. 736,892, filed September 10, 1924, and Serial No. 12,883, filed March 3, 1925.

I claim:

1. The process of making a light weight insulating block and reenforcing it and inserting it in a wall structure while still green, which comprises casting the body of

the block in a mold from plastic material adapted to expand by chemical action and set in cellular condition in bonded relationship to a base member of fibrous material held stationary in said mold, said body material being exposed at the edges and one face of the block, and shaping said block while still plastic into intimate engagement with the adjacent elements of a wall.

2. The process of making a light weight insulating block and reenforcing it and inserting it in a wall structure while still green, which comprises casting the body of the block in a mold from plastic material adapted to expand by chemical action and set in cellular condition in bonded relationship to a base member of fibrous material held stationary in said mold, and then before the block has completely set breaking down the cellular formation at the face opposite said base for strengthening the green block while at the same time leaving the body material exposed at said face as well as at the edges of the block, and then shaping the edge portions of the block while still plastic into intimate engagement with the adjacent elements of a wall.

Signed at Chicago, Illinois, this 27th day of February, A. D. 1925.

HAROLD S. ASHENHURST.
